Primary Examiner — Katherine A Holbrow*Assistant Examiner* — Erin F. Keister(74) *Attorney, Agent, or Firm* — Fish & Richardson P.C.(57) **CLAIM**

The ornamental design for a display panel with animated graphical user interface, as shown and described.

DESCRIPTION

FIG. 1 is a front view of a first image in a sequence for a display panel with animated graphical user interface, showing our design;

FIG. 2 is a second image in the sequence;

FIG. 3 is a third image in the sequence;

FIG. 4 is a fourth image in the sequence; and,

FIG. 5 is a fifth image in the sequence.

The appearance of the transitional image sequentially transitions between the images shown in FIGS. 1-5. The process or period in which one image transitions to another forms no part of the claimed design.

The outermost broken line rectangle depicts the environmental structure of an electronic housing; the second outermost broken line rectangle depicts a display panel; the remaining broken lines depict portions of the graphical user interface; all broken lines form no part of the claimed design. The outermost solid line rectangle depicts a portion of the graphical user interface and is part of the claimed design as shown.
